HEAT TRANSFER DEVICE

Benjamin F. Berkheimer, Greenville, Ohio

Application May 28, 1938, Serial No. 210,754

5 Claims. (Cl. 126—4)

This invention relates to a stove and more particularly to a dual purpose stove used as a combination heater and cook stove.

An object of this invention is to provide panels 5 functioning as walls of a stove, which panels may be removed and replaced without removing any casting from the stove.

Another object of this invention is to provide an enameled panel that may be replaced without 10 removing any of the parts from the stove.

Another object of this invention is to provide an enameled panel having a sheet metal base which interlocks with the castings on the stove in such a manner that the panel may be removed 15 without removing any of the castings from the stove.

Another object of this invention is to provide removable walls, which walls cooperate with the remaining stove structure to form air circulating 20 passages.

Another object of this invention is to provide a cook stove having air passage openings near the top and bottom, permitting cold air to be drawn in near the bottom and expelled at the top.

Another object of this invention is to provide 25 a combined heater and cook stove that is easily produced, cheap, at the same time economical and efficient, presenting a neat appearance and requiring a small space.

Other objects and advantages reside in the construction of parts, the combination thereof and the mode of operation, as will become more apparent from the following description.

Referring to the drawings,

Fig. 1 discloses a perspective view of a stove 30 with the side panel in readiness for insertion.

Fig. 2 discloses a side elevation with the panel inserted in "up" portion, prior to being moved laterally into position.

Fig. 3 discloses the side panel in position.

Fig. 4 is a fragmentary cross sectional view taken substantially on the line 4—4 of Fig. 1.

Fig. 5 is a fragmentary cross sectional view taken substantially on the line 5—5 of Fig. 4.

Fig. 6 is a bottom view of the stove with a portion of the shipping crate assembly in position.

Fig. 7 is an end elevation with parts of the base broken away and shown in section to show the shipping cleats.

Fig. 8 is a fragmentary detail view showing a portion of the base dove-tailed to receive a tenon projecting downwardly from the bottom of the stove.

Fig. 9 discloses a cross sectional view taken substantially on the line 9—9 of Fig. 8.

Fig. 10 is a longitudinal cross sectional view taken through the fire-box and grates.

Fig. 11 is a cross sectional view taken substantially on the line 11—11 of Fig. 10.

Fig. 12 is a fragmentary detail view showing the 5 method of inserting the fire-box lining.

Fig. 13 is a perspective view of a modification of the stove, with parts of the walls broken away to disclose the various compartments within the 10 stove.

Fig. 14 is another modification similar to the modification shown in Fig. 13; but showing legs instead of a continuous base.

Fig. 15 is a perspective view of the panel.

Figs. 16 to 18 disclose fragmentary views of the 15 grate support located in the front end of the stove.

In conventional cook stoves the frame or the housing is either exposed to the atmosphere or it may be covered with insulating material, so as 20 to prevent radiation of heat. In the embodiment disclosed herein, the cook stove has been provided with an outer shell on either side, cooperating with suitable apertures in the bottom and in the top of the stove for circulation of air, so that 25 the stove may be used both as a cook stove and as a heater. In this respect this stove is ideally adapted to supplement the use of electric ranges or gas ranges in the kitchen or elsewhere, this stove being used to both furnish heat as a cook 30 stove and to furnish a heater for the room. Furthermore, the stove has been constructed and arranged so as to be easily shipped and assembled at destination. In order to facilitate shipping, the base of the stove has been provided with 35 downwardly projecting lugs engaging cleats in the bottom of the crate, which lugs cooperate with the cleats in holding the stove in position within the crate.

In the event the enameled side panels of the 40 stove should be damaged in shipping, these side panels may be replaced without removing any of the cast iron portions of the stove. This permits replacement of damaged panels without involving a great amount of labor in replacing the 45 defective panels. These panels are held in position by a plurality of lugs projecting downwardly from the top of the stove and rearwardly from the front of the stove, which lugs engage suitable slots in inwardly directed flanges integral with 50 the panels. The rear side and the bottom side of the panel may be held in position by suitable screws extending into the back of the stove and up into the base thereof.

The shaker for the grates has been placed on 55

- the back end of the stove. The ash removal drawer is located in the front end of the stove. The grate shaker may be operated without opening any doors in the stove. This permits shaking the ashes without the escape of dust into the room. The connection between the grate and the handle is partially obstructed from view by being seated in a cup-like depression in the back of the stove.
- 10 The linings for the fire-box have been removably mounted. These, however, are locked in position, so that clinkers or unburned fuel, or any other solid matter, will not dislodge the removable linings when the grates are shaken.
- 15 Each leg of the stove is held in position by one bolt, cooperating with a tongue angularly disposed with respect to the flanges constituting the body portion of the leg and a plurality of lugs in the base of the stove, to hold the leg in a rigid position. This permits of easy assembly, a low number of parts, resulting in a very substantial supporting structure for the stove.
- In the preferred modification no legs have been used; but the stove has been mounted upon a base 25 extending throughout the entire periphery of the stove and resting upon the floor. In this modification a utility cabinet is found below the ash pit. This may be used for storing kitchen utensils or any other articles to be concealed.
- 30 Referring to Fig. 1, the stove 20 is mounted upon a plurality of legs 22. Each of the legs 22 consists of a pair of flanges 24 angularly disposed relative to each other, so as to form a right angle, as may best be seen by referring to Fig. 35. A supporting tongue 26, forming an angle of substantially 45° with respect to each of the flanges 24 and bisecting the angle formed by the flanges 24, extends along the bottom 28 of the stove. The tongue 26 is provided with a rib 30 40 projecting downwardly, the bight of which straddles a transversely disposed lug 32. The lug 32, extending at an angle of substantially 45° with respect to the sides of the stove, positions the tongue 26 and the legs 22. In order to further 45 position the legs, a pair of lugs 34, one on each side of the tongue 26, parallel to each other and at right angles with respect to the lug 32, forms a channel for aligning the tongue 26. The tongue is held in position by a wing screw 36 50 threadedly engaging the base 28 at 38. From the foregoing structure it may readily be seen that each leg 22 is accurately positioned by the tongue 26 being seated in the channel formed by the lugs 34 and furthermore positioned by the transverse lug 32 seated in the bight opposite the rib 30. A single bolt or fastening member 36 holds the leg in proper position.
- The base 28, in addition to the lugs 32 and 34, 55 is also provided with a plurality of longitudinally extending lugs 40 and transverse lugs 42. These lugs are utilized in shipping the stoves, that is, for holding the stove in position in the shipping crate, as may best be seen by referring to Figs. 6 and 7. Transverse supporting members 44 60 suitably secured to the shipping crate 46 are provided with cleats 48 snugly fitting between the longitudinally extending lugs 40 and the transverse lugs 42, so as to hold the stove in position with respect to the crate. During transit this 65 prevents the sides of the stove being damaged by bumping against the sides of the crate. In the event the stove is damaged in shipping, the more vulnerable parts thereof may be replaced without dismantling the entire stove.
- 70 The front end 50 of the stove is preferably made

from cast iron faced with enamel. This front end piece is provided with a plurality of rearwardly extending lugs 52 on either side thereof for engagement and support of a panel 56, which will be more fully described later. The top frame 58 is also made from cast iron. It is provided with drooping or overhanging ledges 60, one on either side, provided with a plurality of vent holes or air passages 62. This overhanging ledge portion 60 is provided with a plurality of downwardly projecting lugs 64 for holding the panel 56 in position. The rear end 66 is also preferably made of cast iron.

The sides of the stove are covered with removable panels 56, as may best be seen by referring to Fig. 15. Each panel 56 is provided with inwardly projecting flanges 68, 70, 76 and 77. The inwardly projecting flange 68 extends along the top of the panel when it is in position. The inwardly projecting flange 70 extends along the front edge of the stove when the panel is mounted on one side and along the rear of the stove when the panel is mounted on the other side. The flange 76 extends along the rear of the stove when the panel is on the one side and along the front of the stove when the panel is on the other side. The flange 68 is provided with oblong or rectangular apertures 72, one for each of the lugs 64, so that the panel may be raised into position with the forward flange 70 or 76, as the case may be, clearing the lugs 52. Flanges 70 and 76 are provided with a plurality of apertures or rectangular openings 74, one for each of the lugs 52.

When the panel 56 is mounted on one side of the stove, the openings 74 in the flange 70 register with the lugs 52 when the panel is in the "up" position as shown in Fig. 2. After the panel has been positioned as shown in Fig. 2, it is moved forward, or to the right as shown in this figure, to cause the lugs 52 to enter the apertures or rectangular openings 74 in the flange 70. When in this position the flange 76, extending inwardly from the rear edge of the panel 56, overlaps the rear end frame of the stove and is secured in position by a plurality of bolts or screws passed through the rectangular openings 74. The screws may threadedly engage the end frame 66 or nuts may be used on the inside of the end frame, preferably the bolts thread the end frame. The flange 77 along the bottom of the panel is provided with a plurality of openings 78 which receive bolts threadedly engaging the bottom of the stove. From the foregoing it may readily be seen that the panel is held in position by the lugs 52 and 64 cooperating with the bolts. When the panel is placed on the other side of the stove, the flange 76 registers with the lugs 52 and the flange 70 overlaps the rear of the stove. Thus, it is seen that the same panel 56 may be used on either side of the stove without any alteration whatsoever. The panel 56 is inserted and may be removed and another replaced without removing any casting from the stove. This facilitates replacement in the event the panel is damaged in shipment or otherwise.

The flue collar 80 in the top piece 58 is located near the back of the stove. In front of the flue collar is found a pan top 82, provided with a circular opening receiving a stove lid 84. This may be eight inches in diameter, or any other suitable dimension desired.

The fuel feed door or lid 86 is located in front of the pan top and is provided with a downwardly projecting lip or extension 90, so as to

cover the opening in front of the pan top and the opening in the top of the end frame 50. By providing an opening in the end frame, larger pieces of fuel may be fed into the stove than if the fuel feed opening were located exclusively in the top of the stove. The lid may be raised by manually lifting the handle 88, suitably attached to the fuel feed lid 86. The top of the lid 86 is provided with check draft openings 87, which also 0 act as a hot blast when burning bituminous coal. The check draft damper 89 is controlled by actuating the handle 88 to the right or to the left, as the case may be.

As may be best seen by referring to the transverse cross sectional view shown in Fig. 11, side walls 100, one on either side of the fire-box, which will be later described, cooperate with the panels 56 to provide a channel or an air passage from the bottom of the stove to the top. The bottom of the stove, as may be seen by referring to Fig. 6, is provided with several oblong apertures 102, forming air passages registering with the air passage or space between the panels 56 and the side walls 100. As already stated, the air escapes 5 through the opening 62 in the overhanging ledge 60, so as to permit the air to circulate, absorbing heat from the side walls 100, so as to heat the air in the room surrounding the stove.

Near the upper part and on the inner side of 0 the side walls 100 are found a plurality of inwardly projecting ribs 104, vertically disposed in parallel relation to each other. The lower edge or end of the ribs 104 constitute abutments for the fire-box lining members 106, three along each 5 side in the modification as best seen in Fig. 10. There is a fire-box lining 110 along the front end of the fire-box and another fire-box lining 112 disposed in the rear end of the fire-box.

As may best be seen by referring to Fig. 12, 0 each of the fire-box lining members 106 is provided with an aperture 114 near the top, registering with an arcuate hook-shaped portion 116 integral with the side walls 100. The fire-box lining is positioned by rotating the lining so as to cause the arcuate hook 116 to register with the aperture 114 until the stop 118 engages the side walls 100, as clearly shown in Fig. 11. The front end fire-box lining 110 is provided with a seat engaging the grate supporting device, which will 5 be described more fully later. When the fire-box linings are in this home position, clinkers or any other solid matter found on the grates 120 will not displace or dislodge the fire-box lining members 106, for the reason that the upper edges of members 106 abut the lower ends of the ribs 104, the ribs 104 forming stops for the lining members 106.

The side walls 100, provided with ribs 104 and hooks 116, are interchangeably mounted, so that the side walls 100 may be used either on the left side or on the right side. Furthermore, the lining members 106 located on the sides of the fire-box are also interchangeable, for use on the right side of the fire-box or on the left side thereof.

As may best be seen by referring to Figs. 16 to 18, the forward ends of the grate members 120 are journalled in a bearing support 121 transversely disposed and spanning the distance between the side walls 100. Member 121 is preferably held in position by a plurality of lugs 122 projecting inwardly from the side walls 100. Member 121 is provided with a pair of hooks 123 extending upwardly adjacent a cut-away passage 125, so as to form seats 127. The grate member may be inserted by raising the end of

the grate member through the clearance 125 over the hook 123.

After the grate members have been placed in position, a retaining plate 128, provided with an ear 128a, an aperture 128b and a pair of grate receiving holes 128c, is mounted in front of member 121 by extending the ear 128a into an apertured lug 126 and passing the hole 128b over the end of the bolt 129 to hold the grate members in position by the ends thereof projecting through the holes 128c. The plate 128 is held in position by a wing nut 129a engaging the bolt 129. Two gear sectors 133 are slipped over the end of the grate members prior to the mounting of the plate 128 and nonrotatably mounted thereon for driving the two grate members in unison, but in opposite directions, so that when one of the grate members is rotated by the shaker arm 130 the other is rotated also.

The grate members 120 are interchangeably mounted. One end 120a of each grate member is longer than the opposite end 120b. If the grate member supporting the shaker arm is defective and is to be replaced, the replaced grate member has the end 120a projecting through the rear bearing 131. The other grate member has the end 120b terminating in a journal in the rear of the stove and the long shank end 120a mounted in the front end of the stove. By this arrangement the grate members are interchangeable, so that it makes no difference which grate member is to be replaced. It is merely necessary to order member 120 and it can be used either on the left hand side or the right hand side. The grate member may readily be replaced by merely unscrewing the thumb nut 129a from the bolt 129 and removing member 128 from its position, when either grate member may be removed from the front end by merely raising the particular grate member from the hook 123 and letting the forward end drop down through the passage 125, when it may be pulled forward out of the bearing in the rear of the stove. Obviously, if it is the grate member that carries the shaker arm, the screw 132 holding the shaker arm 130 is unscrewed and the shaker arm removed.

An opening 140 in the rear end 66 is aligned with the bearing receiving the end 120b of the grate member 120 that is not actuated by the shaker arm 130. A name plate 142 is held in position by suitable screws and overlies this opening, so that the name plate has a dual-functional purpose. It serves as a name plate and as a cover plate.

In the event the stove is installed in a position such that the shaker is not readily accessible in the position shown, the name plate 142 shown in Fig. 7 may be removed, the shaker arm 130 connected to the end of the other shaker and the name plate inserted over the cup-shaped recess vacated by the shaker shown in Fig. 10, so that the shaker arm may be attached to either grate to suit the convenience of the user of the stove.

In order to provide a tortuous path for the spent gases, such as smoke and the like, escaping from the burning fuel, a baffle 150 is placed immediately in front of the flue opening and is held in position by a suitable lug 152 held in 70 position by a screw 154.

Below the grate members is located an ash pit compartment 156, as may best be seen by referring to Fig. 13. This is provided with an ash pan 158 removable through the door 160 in the 75

front end of the stove. This door is preferably held in position by a piano type hinge 162.

The side walls 100 are provided with draft openings, angularly disposed and controlled by a damper 164, provided with a handle 166, projecting through the front end of the stove and terminating in a knob 168. There is one damper for each side of the fire-box, as may best be seen by referring to Fig. 13.

10 In this figure the stove has been mounted upon a continuous base 169 extending around the entire periphery of the stove. The base 169 is held in position by tenons 173 integral with and projecting downwardly from the bottom 28, fitting into mortises 175 in the ends of the base 169. The stove body proper is deeper than that disclosed in the preferred embodiment. This permits of utilization of the space below the ash pit as a utility cabinet 170. In this modification longitudinal apertures 172 are found in the sides of the base, permitting the air to flow in through the side, up through the holes in the bottom of the stove, through the air passages and expelled from the holes at the top of the stove.

25 In the embodiment shown in Fig. 14 a stove body like that disclosed in Fig. 13 has been disclosed; but instead of being mounted upon a continuous base, this stove body has been mounted upon four short legs, probably three to four inches in height. This also permits of the use of a utility cabinet 170 under the ash pit. When a utility cabinet is provided, it is preferably accessible from the front through the door 174, 30 symmetrically disposed with respect to the ash pit door and the same size, so as to harmonize in appearance.

35 The rear end piece 66 of the stove is provided with horizontal ribs 200 and vertical ribs 202 for reenforcing the rear of the stove and giving it 40 rigidity. The rear end piece 66 is provided with a pair of knock-out plugs 204 and 206 to facilitate the insertion of hot water coils into the firebox.

45 Although the preferred modification of the device has been described, it will be understood that within the purview of this invention various changes may be made in the form, details, proportion and arrangement of parts, which generally stated consist in a device capable of carrying out the objects set forth, in the novel parts, combination of parts and mode of operation, as disclosed and defined in the appended claims.

Having thus described my invention, I claim:

50 1. In a stove assembly having a cast iron front, a metallic top and a cast iron back, the cast iron front portion being provided with rearwardly projecting lugs, the top portion being provided with downwardly projecting lugs, a pair of enameled side panels extending over the sides of the stove, each of said panels being provided with inwardly directed flanges along the sides thereof, the flanges along the front edge and the top being provided with slots for receiving the lugs, 55 the rear edge flange and the bottom flange being provided with apertures and screws for securing the rear edge flange and the bottom flange to the rear casting and the bottom of the stove to hold the side panel in position, the lugs along 60 the front side and extending down from the top

cooperating therewith to rigidly support the panel.

2. In a stove assembly having a frame structure extending along the top, along the front, along the back and along the bottom of the stove, and a pair of panels one for each side, the frame of the stove having inwardly projecting lugs on two sides thereof, each of said panels having inwardly projecting flanges on all sides thereof, the flanges along two sides having apertures registering with the lugs and positioned on the lugs when the panel is in home position, the flanges on the other two sides of the panel overlying the outside of the frame on the corresponding sides of the stove and secured thereto by suitable 15 bolts.

3. In a stove assembly having a cast frame extending along the top of the stove, along the front of the stove, along the bottom of the stove and along the back of the stove, and a pair of panels one for each side for covering the sides of the stove, the frame along the top and along one end being provided with inwardly projecting lugs, each of the panels having inwardly projecting flanges on the sides thereof, the flange along 20 the top having apertures registering with the lugs extending downwardly from the top of the stove, the flanges along either end of the panel being provided with apertures registering with the lugs, the apertures in one flange registering 25 with the lugs on one side of the stove, the apertures in the flange in the other end being adapted to register with the lugs on the other side of the stove, and means cooperating with the flanges on the panels on the sides opposite the 30 lugs for holding the panel in position.

4. In a stove assembly having a top frame member, end frame members and a bottom frame member interconnected to support a firebox, a pair of panels for facing the sides of the 40 stove, said panels having inwardly directed flanges along two adjacent edges thereof, two adjacent edges of the frame having lugs inwardly disposed, said lugs registering with the apertures in the flanges when the panels are in home position, and means for removably securing the other edges of the panels in position.

5. A dual purpose stove assembly for use as a cook stove and a heating stove having a fire-box including side walls inset from the outer edges 55 of the stove along the the sides thereof, the combination including a frame extending along the top along the two ends and along the bottom of the stove and having a width substantially equal to the maximum width of the stove, removably mounted panels for covering the sides of the stove, each of said panels being provided with a pair of inwardly directed flanges one along the front edge of each panel and the other along the rear edge of each panel, the flanges along the 60 front edge and along the rear edge being identical so that the panels are interchangeable for use either on the right hand side or the left hand side of the stove, said panels being offset with respect to the sides of the fire-box so as to 65 leave an air circulating space between the firebox and the panels, and means for securing the panels in position.
